HEAD COVERING

Arlis L. Crowthers, North Hollywood, Calif.

Application February 27, 1951, Serial No. 212,987

5 Claims. (Cl. 2-207)

1

This invention relates to head covering devices including head band scarves and combinations thereof. More particularly, it relates to a combined head and scarf combination characterized by versatility and convenience of use.

Scarves of the prior art have long been known as simple wrap arounds or for disposition in one or another forms, such as by triangulation, about the head. By the latter use, opposite corners are usually tied diagonally under the chin or at the back of the head. An excessive amount of material is ordinarily required to provide a sizable head covering with a satisfactory drape effect. However, excess of material is likewise required to be wrapped about the head for tying purposes thereby, when used for sports or other casual wear, generating excessive amounts of heat.

Such prior art devices have likewise failed to combine versatility and adaptability to various head sizes with a conveniently usable securing means, preferably secured integrally with an optionally visible or invisible headband and associated scarf. The instant device provides in a head covering a hitherto unachieved versatility considering its simple construction.

In view of the above, it is among the objects of this invention to provide a head covering of new and improved simplicity of design.

It is another object of the invention to provide a head covering of simple construction and relatively optimum utility.

Another objective of the invention is a provision of a head covering of the desired character described combining a banded or unbanded appearance usable, in a waterproof version thereof, as a back covering for the head, and by a simple manipulation, as a front shade or rain hat.

Yet another object of the invention is the provision of a headband and scarf combination having an enlarged area of visible usefulness and highly attractive casual styling.

Yet another object of the invention is to provide a headband optionally integral with a scarf, which may also be releasably secured thereto along a line offset from the center of the scarf to lend special utility to the band while lending a distinctive appearance and useful styling to the scarf.

Among the other objects of the invention are the provision of a new and improved headband and scarf securement and the provision of improvements over prior art devices heretofore intended to accomplish generally similar purposes.

Other and more specific objects and advantages

2

will appear and be brought out more fully in the following specification considered with reference to the accompanying drawings throughout which like parts are designated by like numerals.

In the drawings:

Figure 1 is a perspective view of a combined headband and scarf embodying this invention.

Figure 2 is a rear perspective view thereof.

10. Figure 3 is a plan view.

Figure 4 is a sectional view taken on a line 4-4 of Figure 3.

15. Figure 5 is a schematic view clarifying this aforesaid method of wearing this invention.

Figures 6 and 7 show a second mode of wearing the device.

Figures 8 and 9 show a third mode of wearing the same.

20. Figures 10 and 11 show a fourth mode of wearing the same.

Referring more particularly to the drawings, a headband generally designated by the numeral 10, comprises a scarf portion 11 and a headband portion 12.

25. The scarf portion as shown is square in plan view, as may be seen most clearly in Figure 3, where dotted lines 13 complete the square configuration of the outline of a larger triangular section 14. The dotted portion 13 forms a small triangular section 15. The square shape of the scarf as shown is preferable, although the form may be as any other desired configuration, as round, rectangular, or any other desired rounded or right-lined outline, or any combination of these.

30. The head band 12 is preferably formed of two layers 16 and 17 of a fabric which, like the scarf 11, may be smooth and water-proof, e. g., plastic rubber or the like, or any woven or other drapable material whether cotton, rayon, silk, wool or the like. The headband is preferably tapered towards its ends 18 and 19 and is secured, as between the layers 16 and 17, at its marginal edges

35. 20 and 21 by any suitable edging or stitching, preferably an overcast or buttonhole type of stitch which is looped about said edges for concealing the same, said edges being turned under for better concealment.

40. 45. The band is further provided at the end 18 with a female snap fastener 22 or a like securing element and, spaced inwardly from said female fastener, a row of male fastening members 23 or the like. At its other end 19 said band is looped over and through a fastening ring 24 or

the like to which it is secured as by transverse stitching 25.

The band 12 is secured to the scarf 11 nearer one edge of the latter than the other and preferably as shown, diagonally across one corner thereof to form a smaller triangular section 15 and a larger triangular section 14. A line of stitching 26 passes through only one layer 17 of the headband preferably next adjacent the smaller triangular section 15, but through both said triangular sections 14 and 15 adjacent a fold 27 formed in the scarf for defining said triangular sections and for said securement 26. Said stitching 26 is also preferably spaced inwardly from the edge 21 of said band fold. By this stitching the band 16 in the position most clearly shown in Figure 4, overlies and hides the fold in said position (Figs. 1 through 4). Said stitching 26 is also concealed by the upper layer 16 of the band, through which it does not pass.

In manufacture, it has proven feasible to stitch the edge 21 only after first stitching the line 26.

For convenience of reference, the layer 16 will hereinafter be referred to as the top layer, layer 17 as the bottom layer. The edge 21 will be referred to as the front edge and the edge 20 as the rear edge of said band.

In the use of the present device the end 18 of the band is passed through the loop 24 and the female fastening element 22 snaps over any one of the male elements 23 to secure the band to the head in a manner as shown in the drawing.

As illustrated in Figures 1 through 5, the headband may be worn with the upper layer 16 uppermost and exposed to view, and with the smaller triangular section 15 likewise exposed against and outlined by the corresponding surface of the larger triangular section 14. In the event of a sudden shower, or for purposes of shielding the eyes from the sun, the smaller section 15 may be turned forwardly over the fore part of the head as illustrated in dotted outline (Fig. 1) 28. This may be accomplished likewise when wearing the device as shown in Figures 6 and 7, wherein the smaller triangular section is uppermost. Said section is of a size appropriately adapted for this latter purpose. Normally, however, the device is worn as shown in Figs. 1 through 4 in solid outlines.

If contrast is desired, opposite surfaces of the scarf may be formed of different colors or in different patterns; so likewise may be the headband which may be of the same color on both sides or formed in varying patterns either matching or contrasting with the adjacent or exposed surfaces of the scarf.

In Figures 6 and 7 the under surface of the larger triangular section is uppermost and the smaller triangular section is entirely hidden from view. A small margin 29 of the under surface of the band between the edge 21 and the stitching 26 is exposed to view.

In Figures 8 and 9 the band is hidden from view by the smaller triangular section which is similarly decreased in visibility by a distance equal to the width of the band between the rear edge 20 and the stitching 26. More area, however, is available for covering the face and the fore part of the head for the purposes aforesaid.

In Figures 10 and 11 a larger portion of the band 12 is visible, again between the rear edge 20 of the band and the line of stitching 26.

The instant construction has been described

as integral. It will be apparent, however, that releasable securing means, such as additional snap fasteners, hooks and eyes, buttons or the like, may be employed for securing the scarf 11 to the band 12 in lieu of the row of stitching 26. Moreover, the band may be secured along the underside of the fold 27, said stitching 26 then passing through the layer 16 of the band and securing the same against the underside of the larger triangular section 14. The stitching 26 will not in such case pass through the lower layer 17 of the band. A reversal of parts will thus be achieved while creating a different ornamental appearance of the several modes of use and wear. The appearance may likewise be altered as by rounding selected corners of the larger or smaller sections or giving the same other similar or variegated connections. The use will also be dictated in part by the character of the material employed.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent structures and methods.

Having herein described my invention, what I claim as new and desire to secure by Letters Patent is:

1. In combination with an elongate flat headband of fabric comprising two similar layers sewed together at their edges and having cooperative fastening means at the opposite ends thereof for securing the band about the head of a wearer, of a square scarf having one corner loosely turned back over the main body thereof defining a fold, securement means between the band and the scarf at said fold and passing through said headband, said securement means passing through only one layer of said fabric, being concealed by the other, and being spaced inwardly from but adjacent one edge of said headband and extending longitudinally thereof.

2. In combination with an elongate flat headband of fabric comprising two similar layers sewed together at their edges and having cooperative fastening means at the opposite ends thereof for securing the band about the head of a wearer, of a square scarf having one corner loosely turned back over the main body thereof defining a fold, securement means between the band and the scarf at said fold and passing through said headband, said securement means comprising stitching passing through only one layer of said fabric, being concealed by the other, and being spaced inwardly from but adjacent one edge of said headband and extending longitudinally thereof, said stitching terminating at points spaced inwardly from the corresponding marginal edges of the scarf and from the ends of the band whereby the fabric of the scarf between the stitching and the marginal edges, and the corresponding ends of the band are free of securement to each other, permitting the scarf thereto to drape about the sides of the head as worn.

3. In combination with an elongate flat headband having fastening means at the ends thereof for securing the band about the head of a wearer, said fastening means including a loop at one end of said headband and adapted to receive the other end therethrough, of a scarf having an edge, and

means securing the central portion of said headband to said edge of said scarf, the opposite end portions of said headband being free of said scarf, said means securing said scarf to said headband adjacent one longitudinal edge of the latter.

4. In combination with an elongate flat headband having cooperative fastening means comprising: a loop secured to one end of said band, a snap fastener at the other end thereof, and a plurality of complementary snap fasteners spaced inwardly from said other end in spaced linear series, said first snap fastener and the said other end of said headband being adapted to be passed through said loop and secured to any selected one of said series of complementary fasteners for securing the band about the head of a wearer, a normally flat scarf, and means adjacent an edge of said headband securing the central portion thereof to said scarf, the opposite end portions of said headband being free of attachment to said scarf.

5. A combination as defined in claim 4 wherein the overall width of said scarf, measured in a direction parallel to said headband, is greater than the total length of said headband.

ARLIS L. CROWTHERS.
